UNITED STATES PATENT OFFICE.

FRANK WALTER HOWARD, OF BROOKLYN, NEW YORK, ASSIGNOR TO
XENOPHON STOUTENBOROUGH, OF BROOKLYN, NEW YORK.

FILLING-NOZZLE FOR FLUID-HOLDING TANKS.

SPECIFICATION forming part of Letters Patent No. 696,736, dated April 1, 1902.

Application filed May 31, 1901, Serial No. 62,540. (No model.)

To all whom it may concern:

Be it known that I, FRANK WALTER HOWARD, a citizen of the United States, residing at the borough of Brooklyn, city and State of 5 New York, have invented an Improvement in Filling-Nozzles for Fluid-Holding Tanks, of which the following is a specification.

My invention relates particularly to filling-nozzles for tanks holding such fluids as gasoline, naphtha, and kerosene.

The object of my invention is to provide a valve of simple form that is both fluid and vapor tight and that does not project from the tank.

15 In my improvement the valve-case is tubular and open-ended, with a flaring mouth at one end and exteriorly threaded and perforated at the other end and with a central contracted neck forming a guide for the X-stem of the valve. The threaded end is covered with a cap forming a seat for one end of a 20 spring and the other end of which spring seats against the valve. The outward force of the spring holds the valve firmly to its seat. The 25 valve-case is secured to the fluid-holding tank at a flange surrounding its flaring mouth, and the tank may be filled by simply pressing down the valve and holding the same while the fluid is being poured into the tank, the 30 flaring mouth preventing the fluid spilling.

In the drawings, Figure 1 is an elevation, Fig. 2 a plan, Fig. 3 a vertical section, and Fig. 4 a sectional plan at the line $\times \times$ of Fig. 3, illustrating my improvement.

35 The valve-case or tubular body is made with a flaring mouth a , having a surrounding flange 2; a contracted neck a' at the center of the case; an open end a^2 , exteriorly threaded at 3 and provided with perforations 4.

40 The valve-case is thus open-ended. A cap b , interiorly threaded, screws upon the threaded portion 3 of the valve-case and closes this end of the case, and said cap is provided with a cup-seat 5 for one end of the spring c .

45 The valve-body d is provided with a beveled periphery contacting with a beveled seat at the lower end of the contracted neck a' , and these parts are preferably ground and fitted to form a close joint. The valve-body 50 is preferably provided with an X valve-stem

d' , closely fitting and received within the contracted neck a' and the neck forming a guide for the valve.

A cup-seat 6 is formed on the under side of the valve-body d to receive the upper end of 55 the spring c , and e represents the top of the metal fluid-holding tank, within which the valve-case is received and to which the same is soldered at the flange 2. The spring c normally maintains the valve-body in an elevated 60 position to its seat in the valve-case, so as to close off the exit of fluid or vapor. When the tank is to be filled, the end of a funnel or nozzle may be pressed against the upper surface of the X-stem and by the same the valve be 65 depressed, so as to permit of the entrance of fluid into the tank, which, passing down the valve-case, finds an exit into the tank through the perforations 4, the valve at once closing 70 after pressure upon the stem has been released. This valve is especially adapted for use with motor-vehicle tanks where a supply of fluid is carried for use in actuating the motor mechanism, it being absolutely essential in this class of tanks that the filling-valve be 75 fluid and vapor tight. The flaring mouth has the further advantages of preventing the spilling of the liquid and consequent loss when the funnel is inserted and the liquid passes through the funnel and through the filling- 80 nozzle into the tank; also, the opening in the tank where the flange 2 is secured thereto is sufficiently large to pass therethrough all of the nozzle below the flange, so that the device in its entirety is readily inserted and secured 85 in place.

I claim as my invention—

1. A filling-nozzle for fluid-holding tanks, comprising an open-ended valve-case having a flaring mouth, a reduced cylindrical neck 90 with a valve-seat at the end thereof and an enlarged threaded end portion with openings therein, a valve having an integral X-stem which fits the said reduced neck, a cap fitting upon and covering the enlarged end portion 95 of the valve-case, and a spring between the said valve and cap, substantially as specified.

2. A filling-nozzle for fluid-holding tanks, comprising an open-ended valve-case having a flaring mouth, a reduced cylindrical neck 100

with a valve-seat at the end thereof and an enlarged threaded end portion with openings therein, a valve fitting said seat and having upon one side an integral X-stem movable longitudinally in said reduced neck and an integral cup-seat on the other side, a cap fitting upon and covering the enlarged threaded end of the valve-case and having a central integral cup-seat oppositely placed to the cup-seat

of the valve, and a spring having its respective ends in the said cup-seats, substantially as specified.

Signed by me this 15th day of May, 1901.

FRANK WALTER HOWARD.
